United States Patent

Des. 234,855
Patented Apr. 15, 1975

234,855

MEDALLION

Dorothy K. Allen, Libertyville, Ill. (½ F. H. Noble & Company, 559 W. 59th St., Chicago, Ill. 60621)

Filed June 28, 1973, Ser. No. 374,768

Term of patent 14 years

Int. Cl. D11—02

U.S. Cl. D29—19 R

FIG. 1 is a front elevational view of a medallion showing my new design;

FIG. 2 is a right side elevational view, the left side being a mirror image thereof;

FIG. 3 is a top plan view;

FIG. 4 is a bottom plan view; and

FIG. 5 is a rear elevational view thereof, on a reduced scale.

I claim:

The ornamental design for a medallion, substantially as shown and described.
